DAVID SMITH ANTHONY, OF DURANGO, MEXICO, ASSIGNOR OF ONE-THIRD TO EDWARD WILLIAMS AND ONE-THIRD TO GEORGE F. HABERNIGG, OF DURANGO, MEXICO.

STARTER FOR INTERNAL-COMBUSTION ENGINES.

971,482.

Specification of Letters Patent. Patented Sept. 27, 1910.

Application filed February 12, 1910. Serial No. 543,496.

To all whom it may concern:

Be it known that I, DAVID SMITH ANTHONY, a citizen of the United States, and a resident of Durango, Mexico, have invented a new and Improved Starter for Internal-Combustion Engines, of which the following is a full, clear, and exact description.

My invention relates to engine starters, and it has for its object to provide one which has a drum which may be connected by a cable or other flexible transmission means with a pulley on an engine shaft, there being means adapted to rotate the drum on which the cable is wound, the engine shaft being adapted to be rotated rapidly by this means, and one end of the cable being adapted to slip from a recess in the pulley in which it is disposed, when the starter is used.

Still other objects of the invention will appear in the following complete description.

In this specification I will describe the preferred form of my invention, it being understood that the scope of the invention is defined in the appended claims.

Reference is to be had to the accompanying drawings forming a part of this specification, in which similar characters of reference indicate corresponding parts in all the views, and in which—

Figure 1 is a side elevation of my invention as applied to an internal combustion engine; Fig. 2 is a fragmentary view showing the arrangement of the sheave wheel at the top of the frame; Fig. 3 is a fragmentary view showing the manner in which the shaft is journaled in the lower portion of the frame with the drums thereon, and also the means for locking said drums to the shaft; and Fig. 4 is a sectional view on the line 4—4 of Fig. 3.

By referring to the drawings it will be seen that a frame, having side members 5, is provided, which members are connected at their tops by transverse members 6, and are supported by braces 7. A shaft 8 is journaled in the side members 5 of the frame near their tops, and a pulley 9 is secured to the said shaft. In the side members 5, near their bottom is also journaled a shaft 10 on which are mounted drums 11 and 12, which are preferably integral, one with the other. A collar 13 extends from the drum 11 and is integral therewith, and has a recess 14 adapted to receive a pin or

tooth 15, connected by a link 16 with a lever 17 which is pivoted to a lug 18 connected with a member 19, secured to the shaft 10, next a bearing 20, in one of the side members 5, in which the shaft 10 is journaled, 60 there being a bearing 21 in the other side member 5 in which the shaft is also journaled. The shaft 10 projects beyond each of the side members 5, a crank 22 being secured to one projecting end of the shaft 10, 65 a ratchet wheel 23 being secured to the other projecting end of the shaft, there being a crank 24 secured to the last-mentioned projecting end of the shaft beyond the ratchet wheel 23. A pawl 25 is pivoted to 70 one of the side members 5 and is adapted to engage the ratchet wheel 23. A cable 26 is disposed over the pulley 9, there being a weight 27 which is secured to one end of the said cable 26, the other end of the cable 26 75 being secured to the drum 12 and being adapted to be wound thereon. A cable 28 is secured to the drum 11 and is adapted to be wound thereon, the said cable 28 being also wound around a pulley 29 on the shaft 80 30 of an engine 31, one of the terminals 32 of the cable 28 being disposed in a recess 33 in the pulley 29, so that when the terminal is so disposed and the cable is wound around the pulley 29, it will obtain a firm 85 hold on the pulley until it is unwound by the rotation of the shaft 10 and the pulley 11, which in turn is rotated by the weight 27 on the cable 26, the cable 26 being secured to the drum 12. 90

In using the invention, the weight 27 is raised to the top of the frame by means of the cable 26 and the crank 24, the ratchet wheel 23 and the pawl 25 being used when this is done. When the weight has been raised to the position near the top of the frame, the cable 28 is wound around the pulley 29, one terminal 32 of the cable 28 being disposed in the recess 33. When this has been done, the pawl 25 is not raised 95 from the ratchet wheel 23, after the weight 27 is raised but must be left in gear until the drums 11 and 12 are released from the member 19, and when the engineer desires to start the engine, the pin or tooth 15 is removed from the recess 14 by means of the lever 17, and the link 16, permitting the drums 11 and 12 to be rotated by the weight 27 connected by the cable 26 with the drum 12, serving as the power to rotate the drums 110

and the shaft 10, the drum 11 drawing on the cable 28 so that it is unwound from the pulley 29, thereby rapidly rotating the shaft 30, thus operating the engine 31, and 5 securing the desired result.

A spool 34 is mounted on the engine shaft 30, so that the engineer may raise the weight 27 by taking a few turns of the cable 28 around the spool while the engine is running. 10

Having thus described my invention, I claim as new, and desire to secure by Letters Patent:

1. In an engine starter, a drum adapted 15 to rotate, a pulley, a weight, a cable secured to and adapted to be wound on the drum, the cable extending over the pulley and being secured to the weight, and a cable secured to the drum and adapted to be wound 20 on the engine shaft.

2. In an engine starter, a frame, a shaft journaled in the frame, a drum rotatably mounted on the shaft, there being a recess in a member of the drum, a pin connected 25 with the shaft and adapted to be disposed in the recess in the drum to hold the drum relatively to the shaft, a weight, and a cable connected with the weight and adapted to be wound on the drum.

3. In an engine starter, a frame, a shaft journaled in the frame, a drum mounted on the shaft and having a recess, a pulley, a weight, and a cable connected with the weight and adapted to be wound on the 35 drum, a pin adapted to be disposed in the recess, and a lever pivoted to a member connected to the shaft, the lever being connected to the pin.

4. In an engine starter, a frame, a shaft 40 journaled in the frame, two drums mounted on the shaft, there being a recess in a member of one of the drums, a tooth adapted to be disposed in the recess, a lever pivoted to a member of the shaft, a link connecting the 45 lever with the tooth, a pulley, a weight, a cable connected with the weight, the cable being disposed over the pulley and being adapted to be wound on one of the drums,

an engine shaft, a pulley thereon, and a second cable adapted to be wound on the pulley 50 of the engine shaft and on the other drum.

5. In an engine starter, a frame, a shaft journaled in the frame, a drum mounted on the shaft, a cable adapted to be wound on the drum, an engine shaft, a pulley mounted 55 on the engine shaft and having a recess, said cable being adapted to be wound on the pulley, a second pulley, a cable disposed over the second-mentioned pulley, and a weight secured to one terminal of the cable, the last-mentioned cable being adapted to be wound 60 on the drum.

6. In an engine starter, a frame, a shaft journaled in the frame, a drum on the shaft, there being a recess in a member of the 65 drum, a tooth adapted to be disposed in the recess, a lever pivoted to a member connected to the shaft, a link connecting the said member with the tooth, a pulley, a weight, a cable connected with the weight, 70 the cable being disposed over the pulley and being adapted to be wound on the drum, an engine shaft, a pulley thereon having a recess, and a second cable adapted to be wound on the pulley on the engine shaft and 75 on the drum, the terminal of the second-mentioned cable being adapted to be disposed in the recess in the pulley on the engine shaft.

7. In an engine starter, a frame, a shaft 80 journaled in the frame, a drum mounted on the shaft, a cable adapted to be wound on the drum, an engine shaft, a pulley mounted on the engine shaft, said cable being adapted to be wound on the pulley, a second pulley, a 85 cable disposed over the second-mentioned pulley, a weight secured to one terminal of the cable, the last-mentioned cable being adapted to be wound on the drum.

In testimony whereof I have signed my 90 name to this specification in the presence of two subscribing witnesses.

DAVID SMITH ANTHONY.
